UNITED STATES PATENT OFFICE.

THOMAS M. DUDGEON, OF AVALON, PENNSYLVANIA.

GARBAGE-CAN.

1,100,012.

Specification of Letters Patent. Patented June 16, 1914.

Application filed May 15, 1913. Serial No. 767,935.

To all whom it may concern:

Be it known that I, THOMAS M. DUDGEON, a citizen of the United States, and resident of Avalon, in the county of Allegheny and 5 State of Pennsylvania, have invented a new and useful Improvement in Garbage-Cans; and I do hereby declare the following to be a full, clear, and exact description thereof.

My invention relates to garbage and like 10 cans.

The object of my invention is to provide a sanitary can of this character in which the lid can be lifted and thrown to one side by the foot of the user and the contents of a 15 receptacle discharged into the open can, and when the foot is removed the lid automatically returned and dropped into position over the can so as to always insure the can being properly covered and without the ne- 20 cessity of handling the lid on the part of the user.

Furthermore, it is my object to provide for the introduction of a disinfectant continuously in minute quantities into the can 25 so that the flies are eliminated and the offensive odor removed.

To these ends my invention consists, generally stated, in a base or support, a can adapted to rest thereon and removable therefrom, a frame supported by the base, a vertically movable and rotary rod on said frame, a lid carried by said rod, a guide on said frame having a cam-slot therein, a pin on said rod engaging said cam-slot, and a 35 lever engaging said rod to lift the same whereby the said rod and the lid is first lifted to clear the top of the can and then swung in a horizontal plane to one side to open the can.

40 The invention further comprises certain other features all of which will be fully hereinafter set forth and claimed.

In the accompanying drawings Figure 1 is a side elevation of my improved can, the open 45 position of the can being indicated by dotted lines; Fig. 2 is a sectional view of same; Fig. 3 is a plan view the open position of the can being indicated by dotted lines; Fig. 4 is an enlarged view of the disinfectant dis-

tributer; and Figs. 5, 6, 7, 8 and 9 are details, Fig. 8 being a section on the line 8—8 Fig. 5 looking in the direction of the arrows.

In the drawing the numeral 2 designates a base which may be formed of cast or sheet metal of sufficient weight to give it the necessary stability, said base being formed with the depression 3 to receive the bottom ring 4 of the can 5. The standard 6 is secured by screws 7 or other suitable fastening devices to the base 2, said standard being made up of the two angle-bars 8 and 9. At the point where said angle-bars are connected to the base 2 said base has the outwardly projecting portion 10 into which said screws enter. A sleeve portion 11 is inserted between the angles 8 and 9 at the lower end thereof and secured to said sleeve-portion is a second sleeve-portion 12 which together with said first portion forms a sleeve or guide for the rod 13. The sleeve-portion 11 has the lugs 11^a and the portion 12 has the wings 12^a which fit between said lugs, so that when said portion 12 is secured to the angle-bars 8 and 9 by screws the inner sleeve-portion 11 is held in place by said outer portion. Each of the portions 11 and 12 has the bearings 12^b at each end with which the rod 13 engages. This rod 13 is provided with the stud 14 which engages the cam-slot 15 in the sleeve-section 12. This cam-slot 15 has at the lower end the vertical portion 16 for the purpose fully hereinafter set forth. At the upper end of the standard 6 is the bearing 17 through which the rod 6 passes and by which it is guided. The upper end of the rod 13 is provided with a horizontal arm 18 which enters the seat 19 in the casting 20 which is riveted or otherwise secured to the lid 21. A pin 22 secures the arm 18 within the seat 19.

The casting 20 is provided with the seat 23 for the glass tube 24 and said casting is also provided with the peep-hole 25. The upper end of the casting 20 is threaded, as at 26, and a can 27 with the threaded connection 28 is supported by said casting 20 by engaging the threaded portion 26. The can 27 form a receptacle for formaldehyde or

some other suitable disinfectant, and in order to control the flow of said disinfectant from said can I provide the needle-valve 29 which passes down through the valve-seat 30. The upper end of the needle-valve 29 is threaded as at 31 and passes through the threaded nut 32 on the top of the can 27. A cap 33 is provided to cover the top of the valve 29 and the top of said needle-valve is milled as at 34 to receive a suitable key to regulate the position of said valve. An inlet 35 is provided for admitting the formaldehyde to the can. By having the threaded portion 31 of the valve end where it does it would be impossible for any one to completely withdraw the valve by turning the upper end. On the inside of the lid 21 is the spreader 36 which is supported by the straps 37 and said spreader acts to deflect the drops of formaldehyde coming from the can and scatters them over the contents of the garbage-can.

The lower end of the rod 13 is engaged by the end of the treadle 38, said treadle being fulcrumed on the pin 39 secured to the base 2, and said treadle extending around toward the front of the can in convenient position to be reached by the foot of the person opening the can and standing in front of same. The treadle has a slight amount of lateral play on the pin 39 and the foot-portion 40 of said treadle is adapted to be pushed under the retaining lug 41 on the base 2 where it is desired to retain the lid of the can in its open position, as fully hereinafter set forth.

When it is desired to use the can the foot is placed upon the foot-lever 38 and the outer end of the foot-lever lowered, which will raise the inner end, and the rod 13 will be elevated. The first movement of the rod 13 will be in a vertical direction due to the vertical portion 16 of the cam-slot 15 and as the rod is lifted the lid 21 is also lifted until its overhanging flange clears the top of the can. When this is accomplished the pin 14 of the rod 13 enters the spiral portion of the cam-slot, and the rod 13 is rotated and the lid 21 is thrown aside in a horizontal plane as indicated in dotted lines Figs. 1 and 3. In this manner the can is opened and the garbage in the receptacle in the hands of the user may then be discharged into the can, whereupon the foot is lifted from the treadle and the lid returns automatically to its usual position, due to the weight of said lid and the rod 13. The lower end of the rod 13 will first bring the lid back to the position over the can, and when the pin 14 enters the vertical portion 16 of the cam slot the lid drops down with its flange overhanging the top of the can. If, however, it is desired to hold the lid in its open position to remove the can from

the base and to dump the garbage from the can, the operator simply slips the treadle 40 upon the retaining lug 41, whereupon the lid will be held in its open position and the can be lifted and its contents discharged and then set back again on the base 2 without any interference on the part of the lid. Just as soon as the operator releases the treadle from the retaining lug 41 the lid swings back and drops into its closed position without any attention on the part of the operator. By having the automatically closing lid I insure the return of the lid to the can to close the same, and being supported in the way illustrated and described the lid has no opportunity to fall and become dented and distorted in shape so that it will not fit the can, and the contents of the can are free from attack by dogs and flies.

The formaldehyde or other disinfectant contained in the can 27 is always distributing into the can and the rate of discharge is controlled by the valve 29 so that only a drop at a time passes and in this way a can full of formaldehyde will last for a long time. By having the upper end of the valve 29 key-operated and covered with the cap 33, malicious tampering with the valve is prevented. Furthermore, the sight opening or peep-hole 25 permits one to observe just how much of the formaldehyde is passing, and the discharge may be controlled with great accuracy. The spreader 36 acts to distribute the formaldehyde over the contents of the can and in this way the contents of the can are purified and the bad odors removed. The formaldehyde moreover eliminates the flies as they cannot live in the presence of the same.

What I claim is:

1. The combination of a base, a can resting thereon and freely removable therefrom, a standard comprising bars, a guide on said standard comprising an inner portion fitting between said bars, lugs at the upper and lower ends of said inner portion, an outer portion having wings entering the spaces between said lugs and secured to said bars, said outward portion having a cam-slot, a rod passing through said guide, a pin on said rod engaging said slot, a lever engaging the lower end of said rod, and a lid carried by said rod.

2. The combination of a base, a can resting thereon and freely removable therefrom, a standard on said base, a guide on said standard having a cam-slot, a rod engaging said guide, a pin on said rod engaging said slot, a foot-lever fulcrumed on said base and engaging said rod, a lid carried by said rod, and means on said base for engaging the outer end of said foot-lever, whereby said lid is held in open position.

3. The combination of a base, a can resting thereon and freely removable therefrom, a standard on said base, a guide on said standard having a cam-slot, a rod engag-
5 gaging said guide, a pin on said rod engag-
ing said slot, a foot-lever fulcrumed on said base engaging said rod, a lid carried by said rod, and a projection on said base

adapted to engage the outer end of said foot-lever.

In testimony whereof, I the said THOMAS M. DUDGEON have hereunto set my hand.

THOMAS M. DUDGEON.
